DESIGN FOR A TRANSFORMER CASING

Richard C. Hitchcock, Upper Montclair, and Uel L. Smith, Towaco, N. J., assignors to Westinghouse Electric and Manufacturing Company, a corporation of Pennsylvania

Application March 13, 1937, Serial No. 68,162

Term of patent 14 years

To all whom it may concern:

Be it known that we, Richard C. Hitchcock and Uel L. Smith, citizens of the United States, residing, respectively, at Upper Montclair, in the county of Essex and State of New Jersey; and Towaco, in the county of Morris and State of New Jersey, have invented a new, original, and ornamental Design for a Transformer Casing, of which the following is a specification, reference being had to the accompanying drawing constituting a part thereof.

Figure 1 is a plan view of a transformer casing designed in accordance with the invention;

Fig. 2 is a view in side elevation of the casing shown in Fig. 1; and

Fig. 3 is a view in end elevation of said casing.

We claim:

The ornamental design for a transformer casing, substantially as shown.

RICHARD C. HITCHCOCK.
UEL L. SMITH.
